FUSE CABINET

Filed Jan. 12, 1927

Harrison J. L. Frank *INVENTOR.*
BY *Francis D. Hardesty*
ATTORNEY.

UNITED STATES PATENT OFFICE

HARRISON J. L. FRANK, OF DETROIT, MICHIGAN

FUSE CABINET

Application filed January 12, 1927. Serial No. 160,751.

The present invention relates to fusing devices and especially to such devices for heavy fuses, and it has among its objects means in which the fuses when conducting current are entirely insulated and therefore cannot be touched accidentally.

Another object is a device of the character indicated which can be used as a safe form of switch without removal of the fuses.

Other objects will readily appear to those skilled in the art upon reference to the following description and drawings, in which:

Fig. 1 is a front elevation of a cabinet involving the invention and adapted for two fuses;

Fig. 2 is a vertical section on line 2—2 of Fig. 1;

Fig. 3 is a cross section on line 3—3 of Fig. 1;

Fig. 4 is a section on line 4—4 of Fig. 1; and

Fig. 5 is a section like that of Fig. 4 but with the fuse block reversed.

In the drawings there is indicated at 10 a metal cabinet provided with a flanged cover 11 having a depressed central portion 12 cut out at its central part and forming a mask for that part of the interior of the cabinet surrounding the fuse block (to be described in detail) and forming a chamber or compartment 13. Over the depressed portion 12 may be hinged a door 14 as shown in Fig. 1.

The fuse block consists of a rectangular cup or cup-shaped socket of insulating material 20 having at each end an extension or foot 21 and one or more openings 22 to the inside of the cup immediately above the foot 21. Also, at each end inside the cup is a vertical rib or part of a dividing wall 23.

The current carrying wires 29 are led into the cabinet 10 through suitable openings and secured to contact members 30 on top of the feet 21, as shown in Fig. 2, which members 30 extend through openings 22 to the interior of cup 20 at the ends thereof and are of spring material and divided as shown in this figure so that a co-operating finger or blade may be inserted between them. It is preferred to protect the members 30 against accidental contact with the ends of the fuses by securing

in block 20 strips 20^a of insulating material extending up in front of the members 30 as indicated in Fig. 2.

Co-operating with cup 20 is a block 35 adapted to fit into the cup. This block is rectangular in its upper portion and is provided with a rib 36 co-operating with the lower portions of ribs 23 to divide the lower part of the cup interior into two compartments. The block at each end has vertical grooves co-operating with ribs 23 and thereby guiding the block during insertion.

The under side of the block on each side of rib 36 is provided with fuse holding clips 37 to which are attached the L-shaped contact blades 38 extending somewhat beyond the clips and downwardly so as to be adapted to be inserted between the two parts of members 30 indicated in Fig. 2.

Block 35 is removable with the fuses 40 in clips 37 so that the fuses may be replaced with safety. It is also reversible so that the contact members are separated by the insulating material of the block and completely covered thereby. When the block is reversed the members 30 support the block by means of shoulders 45 which extend over the members. In this reversed position, of course, no current can flow through leads 29 and the device may therefore be used as a switch.

In order to facilitate the removal of the block 35 a small bail or handle 35^a is provided, which bail is preferably hinged so that it will be flat when not being used.

It is also preferred to make the block and cabinet of such relative proportions that the door of the latter in closing will push the part 35 into its final position if this has not already been done by the operator.

While the cabinet has been described as adapted for two fuses, it is of course obvious that it may be adapted for any number of fuses and such adaptation is contemplated. It is also contemplated to provide blocks 35 with fuse clips for different sizes of fuses so that the same cabinet may be used for systems designed for different currents, or the fuse clips may be omitted and conducting strips used. In this case the device becomes simply a switch.

The device constructed as described provides a neat and compact instrumentality in which the live conductors are completely covered when the block 35 is in place and which 5 provides efficiently against accidental contact with the live terminals when the block is out as such terminals are located within the socket portion and completely surrounded by insulating material.

10 Having now described the invention and the preferred form of embodiment thereof, it is to be understood that the said invention is not to be limited to the specific details herein set forth but only by the scope of the 15 claims which follow.

I claim:

1. In a fusing device, a cup-shaped socket 20 of insulating material having ribs on opposite walls, contact members in the bottom of said socket on opposite sides of said ribs, a fuse block of insulating material having a rib thereon with fuse holding and contact means on either side thereof, said fuse block adapted to fit into said socket and 25 make contact between said means and members with said ribs in alinement whereby to form a dividing wall between said fuses and contacts.

2. In a fusing device, a cup-shaped socket 30 of insulating material having contact members therein connected to suitable conductors, means in said socket to prevent accidental contact with said members and a block of insulating material carrying fuses on one side 35 thereof adapted to fit into said socket and connect said contact members through the fuses, said block also adapted to fit into said socket in reversed position and thereby cover said contact members and separate the fuses 40 from said contact members.

HARRISON J. L. FRANK.
